UNITED STATES PATENT OFFICE.

JOZEF GOLONKA, OF DETROIT, MICHIGAN.

TOBACCO-BOX.

1,360,927.

Specification of Letters Patent. Patented Nov. 30, 1920.

Application filed May 8, 1920. Serial No. 379,796.

To all whom it may concern:

Be it known that I, JOZEF GOLONKA, a citizen of Poland, residing at Detroit, in the county of Wayne and State of Michigan, have invented certain new and useful Improvements in Tobacco-Boxes, of which the following is a specification.

The primary object of the invention is the provision of a match and tobacco holder adapted for the reception of a box of matches readily accessible for use, the box being so arranged as to present the match striking surface of the box readily accessible when the device is closed.

15 A further object of the invention is to provide a tobacco holder with means for holding a box of matches normally inclosed within the device ready for dispensing the matches whenever desired for lighting the same upon the striking surface of the match box.

With these general objects in view, the invention consists of the novel combination and arrangement of parts hereinafter more 25 fully described in connection with the accompanying drawing and in which like reference characters designate corresponding parts throughout the several views.

In the drawing,

30 Figure 1 is a side elevational view of the invention,

Fig. 2 is a similar view of an adjacent side thereof,

Fig. 3 is a longitudinal sectional view 35 taken upon line III—III of Fig. 1,

Fig. 4 is a transverse sectional view of the device taken upon line IV—IV of Fig. 1,

Fig. 5 is a bottom plan view thereof, and

Fig. 6 is a perspective view of the slide 40 or door for the match box receptacle.

My invention being in the nature of a holder for tobacco and matches, broadly consists of a casing 10 having a transverse partition 11 dividing the same into a tobacco 45 compartment 12 and a match compartment 13, the former being normally closed by a hinged cap 14 and the latter by a slide or door 15.

The cap 14 is connected by a hinge 16 50 with the side of the casing 10 whereby tobacco 17 is readily supplied in the compartment 12 and removed therefrom for smoking. The slide 15 is arcuate in cross section conforming to the curvature of the casing 10 and has inwardly projecting flanges 18 positioned over guide ribs 19 upon the

casing adjacent the opposite sides of the opening or doorway 20 for the compartment 13.

A stop lug 21 carried by the casing 10 above the door opening 20 projects through a central longitudinal slot 22 in the slide 15 for limiting the opening movement of the slide preventing the flanges 18 from being accidentally removed from the ribs 19. 65 The lug 21 has a head overlying the slot 22 so that said lug also acts as a guide for the slide 15, the latter when in its closed position being seated upon the outer edge or bead 23 of the casing bottom 24.

70 The usual small match box 25 is slidably positioned within the compartment 13 with one end of the box severed or removed so that the matches 26 within the box 25 are readily accessible upon opening the slide 15. 75 The match striking surface 27 of the box 25 is exposed through an opening 28 in the casing bottom 24 for use in striking matches thereon whether the slide 15 is open or closed.

A roll 29 at the top of the slide 15 affords a handle for grasping in moving the slide 80 relatively of the door opening 20 of the casing 10 and a projection 30, such as a ring, upon the casing 10 above the door opening 85 is adapted for engagement by narrow resilient portions or strips 31 at the top of the slide 15 formed by providing slits 32 in the top portion of the slide and slightly bending the strips 31 inwardly toward the side 90 of the casing 10. When the slide 15 is in its closed position, the strips 31 will pass over the projection 30 thereby retaining the slide 95 closed until manually forced to its open position by sliding the same toward the cap 14.

A serviceable holder for tobacco and matches is provided in which the matches are readily renewable by inserting a new box of matches whenever the supply is exhausted while the tobacco 17 is normally held inclosed within the casing 10 by the cap 14 which tightly fits the open end of the compartment 12. While the form of the invention herein set forth is believed preferable, it will be understood that changes 100 therein may be made without departing from the spirit and scope of my invention.

What is claimed as new is:

1. A holder divided into compartments with an opening for one compartment at 110 the end of the casing and for the other compartment at the side thereof, a sliding clo-

sure for the side opening having a rolled over handle portion slitted upon its inner face providing resilient strips, a projection upon the casing above the side opening 5 adapted for engagement by said strips when the slide is closed, the slide having a longitudinal slot therein, a headed stop lug upon the casing above the side opening positioned through said slide and guide members 10 for the slide at the opposite sides of said side opening.

2. A holder divided into compartments with an opening for one compartment at the end of the casing and for the other compartment at the side thereof, a sliding closure for the side opening having a rolled over handle portion slitted upon its inner face providing resilient strips, a projection upon the casing above the side opening 15 20 adapted for engagement by said strips when the slide is closed, the slide having a longitudinal slot therein, a headed stop lug upon the casing above the side opening positioned through said slide, guide members for the slide at the opposite sides of said opening, the end of the casing opposite said open end thereof having a slot therein, the compartment with the side opening being adapted 25

for the reception of a match box having a match striking surface exposed for use 30 through said slot when the device is assembled for use and a closure cap for the open end of the casing.

3. A holder comprising a casing having a side opening with the adjacent end of the casing provided with a longitudinal slot, a headed stop lug upon the casing above said opening, an arcuate door for the opening substantially conforming to the curvature of the adjacent portion of the casing slidably 40 mounted upon the casing with a longitudinal slot through which said lug is positioned, guide means for the door at opposite sides of the opening, the door being formed of resilient material with an upper rolled 45 over portion forming a handle and further having inwardly bent strip portions, a projection upon the casing above said opening adapted for engagement with said strip portions during the closing of the door, a match 50 box positioned in said casing through said side opening and a striking surface upon the box inwardly of the said slot.

In testimony whereof I affix my signature.

JOZEF GOLONKA.
